DISTORTION WEAVE FABRIC STRUCTURE

Ivar O. Moberg, Spray, N. C., assignor to Marshall Field and Company, Chicago, Ill., a corporation of Illinois

Application November 29, 1950, Serial No. 198,140

9 Claims. (Cl. 139—384)

1

This invention relates to an improved fabric structure and its primary object is to provide a ground or base fabric area having spaced tightly woven areas extending weftwise of the fabric. Between the spaced areas of tightly woven ground fabric there are provided loosely woven or floated areas wherein a substantial number of warp yarns and weft yarns are floated across these loosely woven areas, the floated areas also being spaced longitudinally or warpwise of the fabric with the weftwise tightly woven areas also being spaced longitudinally or warpwise of the fabric between the floated areas.

Upon a predetermined number of picks of the ground fabric being woven to form said tightly woven and loosely woven areas extending weftwise of the fabric, a relatively small number of picks of an effect or design filling, preferably of a greater number of plies or strands per pick than the filling used in forming the ground fabric, are then loosely woven. Now, as these effect fillings are beat-up at the fell of the cloth, due to the previous tightly woven areas and the loosely woven areas, the effect filling will not extend in a straight line between the selvages of the fabric but will extend in an irregular or sinuous path across the fabric.

Thus, upon a series of repeats of the tightly woven and loosely woven areas of the ground fabric being woven and upon the loosely woven effect filling yarns being woven between each of the repeats of the tightly and loosely woven ground yarns, a product is formed having a plurality of sinuous yarns extending thereacross defining the tightly woven areas since, upon the sinuous effect filling yarns being thrown across the fabric, they are bunched or crowded together at the points at which the ground yarns were loosely woven, and a preceding number of picks of the effect yarns are spaced apart from the subsequent filling effect yarns at opposed edges of the tightly woven areas of the ground yarns, the subsequent design or effect yarns being crowded against the preceding effect or design yarns between the tightly woven areas of the ground yarn, due to the floated portions of the ground yarns, at spaced points throughout the width of the woven material.

Some of the objects of the invention having been stated, other objects will appear as the description proceeds when taken in connection with the accompanying drawings, in which—

Figure 1 is a schematic view showing a portion of the means employed for weaving the fabric;

Figure 2 is a fragmentary view of a piece of a typical fabric woven to embody the features of

2

the present invention, the appearance of this fabric being shown as it is woven on a loom;

Figure 3 is a fragmentary elevation of a piece of fabric looking at the opposite side of Figure 2;

Figure 4 is a view similar to Figure 2 but showing the effect produced with the fabric shown in Figure 2 after it has been subjected to various washing, tumbling and finishing operations to which the cloth is subjected following a weaving operation;

Figure 5 is a greatly enlarged fragmentary longitudinal vertical sectional view taken substantially along the line 5—5 in Figure 2;

Figure 6 is an enlarged fragmentary vertical sectional view taken transversely of the fabric and looking substantially along the line 6—6 in Figure 5;

Figure 7 is a greatly enlarged and exploded view of the fabric, being an area substantially as indicated by the broken lines identified at A in Figure 2 but showing the weft or filling yarns extending in a straight line rather than in a sinuous line, as shown in Figure 3, for purposes of clarity;

Figure 8 is a chart of the pattern employed on a pattern means, such as a pattern chain of a loom, for control of the heddles or harnesses.

In Figure 1, there is shown a typical arrangement of the various pertinent weaving instrumentalities of a loom which may be employed in weaving the particular fabric shown in Figures 3 to 8, inclusive. This particular loom may be of a type such as is manufactured by Crompton & Knowles of Worcester, Massachusetts, and which is known as a model C-4 loom with a pattern controlling mechanism such as a dobby head. It will be evident from the context that many other types of looms may be used and also the number of heddles or heddle frames employed may vary in accordance with a desired pattern. Also, many other pattern mechanisms may be used in association with the loom such as a jacquard mechanism. Since at least two different types of weft or filling yarns are employed, it is evident that a suitable shuttle changing mechanism for accommodating at least two shuttles should also be employed in association with the loom on which this fabric is woven.

Referring to Figure 1, a sheet of warp yarns, designated generally at W, is directed from a warp beam 30 over a whip roll 31 and extends forwardly over and under a pair of spaced rods 32 and 33 after which the various yarns of the sheet of warp W are passed through a plurality of successively arranged vertically movable heddle frames or heddles H1 to H8, inclusive, and H1' to

H8', inclusive, the exponent of each of these last-named reference numerals corresponding to the exponent of the reference numerals applied to the warp yarns in Figure 7 and indicating the warp yarn or strand which is controlled by the heddle. Although, 16 heddles or heddle frames are shown in Figure 1, it is to be understood that any desired number of heddles or heddle frames may be employed in accordance with a desired pattern and depending upon the type of pattern mechanism employed in effecting operation of the heddles or heddle frames.

After the warp yarns have passed through the corresponding heddles or heddle frames, they then pass through a conventional reed 35 carried by an oscillatable lay 36 across which filling yarns, to be presently described, are projected in the usual manner to lay the filling yarns in the shed formed by the warp yarns W and to beat the warp yarns into the fell of the cloth or at the beat-up point of the lay indicated at B in Figure 1 to thus form fabric or cloth C.

Now, referring to Figure 7, there is shown the essence of the arrangement of a few of the warp yarns and weft yarns to produce a fabric substantially as shown in Figures 2 to 6, inclusive, and this may be readily compared with the chart of the pattern shown in Figure 8 employed on the usual pattern means for the loom. It is to be assumed that the fabric is formed from the top to the bottom of the illustration in Figure 7, the weft or filling yarns extending crosswise of Figure 7 and the warp yarns extending lengthwise or from the top to the bottom of Figure 7.

There is a single repeat in the patterning with respect to the weft or filling yarns shown in Figure 7, there being a group of twenty-six successively woven base or ground filling yarns F₁ to F₂₆ in a group, identified as group 1A in Figure 7, following which a group of four effect or design filling yarns E₁ to E₄ are woven successively. Then twenty-six additional ground filling yarns F₁' to F₂₆', inclusive, are woven successively in a group identified as group 2A in Figure 7. A group of four additional effect filling yarns identified at E₁' to E₄', inclusive, are then woven to complete a single repeat in the number of picks which are employed in knitting the particular fabric shown in Figures 2 to 4, inclusive.

It will be observed in Figure 7 that the warp yarns are also divided into repeats, each of which includes at least one first group of eight warp yarns, identified as group 1, and at least one second group of eight warp yarns, identified as group 2. The areas identified by the various groups are enclosed by broken lines so their scope may be clearly discernible as the description proceeds. The first group includes warp yarns indicated at W1 to W8, inclusive, and the second group includes warp yarns indicated at W1' to W8', inclusive. Each repeat of the warp yarns should include a plurality of side by side first groups and a plurality of side by side second groups, the number of first groups being substantially the same as the number of second groups in each repeat of the warp yarns. In other words, referring to Figures 2 and 3, there are shown a plurality of warpwise and weftwise spaced tightly woven areas, indicated at 40, between which are woven sleazy or loosely woven areas 41, these loosely woven areas 41 being visible at the back of the fabric only, as shown in Figure 3, since they are covered by the effect or design filling yarns in Figure 2.

It will be observed in Figure 7 that the warp

yarns W3 and W7 in group 1 are interwoven loosely with some of the weft yarns F1 to F26 at one side of the loosely woven effect filling yarns E1 to E4, inclusive, and the other warp yarns W1, W2, W4, W5, W6 and W8 are floated on the top of the filling yarns F1 to F26, inclusive, in group 1A, while at the other side of the effect filling yarns E1 to E4, inclusive, the warp yarns W1 to W8, inclusive, are tightly interwoven with the ground filling yarns in group 2A, including the filling yarns F1' to F26', inclusive.

On the other hand, the warp yarns W1' to W8' are tightly interwoven with the ground filling yarns F1 to F26 in group 1A while they are loosely 15 interwoven with the ground filling yarns F1' to F26' in group 2A as above described for the warp yarns in group 1. Thus, the areas indicated at 20 40 in Figures 2 and 3 are woven in the manner in which the warp yarns W1 to W8, inclusive, and the ground filling yarns F1' to F26', inclusive, 25 in group 2A are interwoven (Figure 7) and in the manner in which the warp yarns W1' to W8', inclusive, are interwoven with the weft yarns F1 to F26 in group 1A. It is evident that each of 30 the areas 40 will include a substantial number of groups of warp yarns, such as the groups 1 and 2 in Figure 7, in order to complete a repeat such as the repeat R in Figure 2. It will be noted that this repeat R embraces two longitudinally extending rows of off-set or staggered areas 40.

Referring now to the upper right-hand portion of Figure 7, it will be observed that the warp yarns and weft yarns embraced by the respective groups 2 and 1A are interwoven to form a very dense and firm fabric. The majority of the ground warp yarns in the area embraced by groups 1 and 1A float, without interweaving, on the face of the fabric and these warp yarns, including the warp yarns W1, W2, W4, W5, W6 and W8 are not interwoven at all with the weft yarns in group 1A. These last-named warp yarns shall be termed as face warp yarns for purposes of description.

45 Inasmuch as the face warp yarns float on the face of the fabric, it is obvious that the portions of the filling yarns therebetween will float at right angles on the back of the fabric. These long floats of the filling yarns on the back of the fabric would be objectionable and, therefore, the two warp yarns **W2** and **W7**, which shall be termed as back warp yarns, are alternately interwoven, for example, with every fifth pick of the floated filling, that is, each of the warp yarns **W2** and **W7** are interwoven, for example, with every tenth ground filling yarn. The portions of the warp yarns which serve as back warp yarns are shaded by stippling for purposes of clarity. The length of floats may be varied without departing from the spirit of the invention.

As heretofore stated, a plurality of groups of warp yarns, such as the warp yarns in group 1, are repeated in side by side relation in accordance with the size of the areas 40 which extend transversely of the fabric (Figure 2) and these groups of warp yarns, which are interwoven with the filling yarns in the manner in which the group 1 of warp yarns is interwoven with the group 1A of the weft yarns in Figure 7, would form a very open and sleazy weave on the back 70 of the fabric, as shown in Figure 3, which will partly cover and thus conceal the long floats of the filling in this area without interfering with the distortion of the effect filling.

After a predetermined number of the ground 75 filling yarns have been cast across the fabric

such as the twenty-six filling yarns **F1** to **F26**, inclusive, in Figure 7, the lesser number of picks, for example, four picks of relatively heavy effect filling are then interwoven with the warp yarns. It will be noted that the area including the warp yarns in group **2** and the filling yarns in group **2A** is formed in substantially the same manner as the area in which the warp yarns in group **1** are interwoven with the weft or filling yarns in group **1A**. Conversely, the warp yarns in group **1** are interwoven with the filling yarns in group **2A** in the identical manner in which the warp yarns in group **2** are interwoven with the weft or filling yarns in group **1A**.

Now, assuming there are several repeats of the warp yarns in group **2** disposed on the right of group **2**, it will be noted that the warp yarns **W4'** is floated above all of the ground filling yarns in group **2A** as well as the effect filling yarns **E4** and **E1'** while the warp yarns **W2'** and **W5'** are floated above all of the ground filling yarns in group **2A**, but extend beneath the adjacent effect filling yarns **E4** and **E1'** and then pass above the effect filling yarns **E3** and **E3'** at opposed ends of the area defined by the ground filling yarns in group **2A**.

On the other hand, the warp yarns **W1'** and **W6'** are floated above all of the ground filling yarns in group **2A** and pass beneath both of the effect filling yarns **E4** and **E3** and above the effect filling yarn **E2** at one end of the group **2A** of filling yarns while, at the other end of group **2A** of the ground filling yarns, the warp yarns **W1'** and **W6'** pass beneath both of the effect filling yarns **E1'** and **E2'** and then pass above the effect filling yarn **E3'**.

The warp yarn **E3'**, of course, passes beneath the three effect filling yarns **E4**, **E3** and **E2** after passing above the effect filling yarn **E1'** and is then floated above all of the ground filling yarns in group **2A** after which it passes beneath the three effect filling yarns **E1'**, **E2'** and **E3'** and then passes above the effect filling yarn **E4'** to subsequently be interwoven with the filling yarns to form a tightly woven area adjacent the lower surface of the effect filling yarn **E4'** in Figure 7 which is identical to the tightly woven area adjacent the upper surface of the effect filling yarn **E1'** in Figure 7. The floats of the warp and filling yarns need not be as described, as they might be interwoven at shorter or longer intervals if desired.

It is well known to those familiar with the art that, upon each beat-up stroke of a reed, such as the reed **35** in Figure 1, the reed **35** advances slightly beyond the point at which it engages the fell of the cloth and, although the reed **35** may be perfectly straight throughout its length, the floated portions of the ground filling yarns, which extend beneath the floated portions of the warp yarns, such as are defined by the groups **2** and **2A**, are beat-up over one another, since the warp yarns are unable to hold them in the same plane as the upper or lower surfaces of the adjacent tightly woven areas such as the area defined by groups **1** and **2A** in Figure 7.

Therefore, upon weaving the area defined by groups **1** and **1A**, the effect filling yarns **E1**, **E2**, **E3** and **E4** would be beat-up thereagainst and would tend to roll over the upper surface of the loosely woven ground fabric, defined by groups **1** and **1A** in Figure 7, and these effect filling yarns **E1** to **E4**, inclusive, would be beat-up against the previous beat-up ground filling yarn **F26** in the area defined by groups **2** and **1A**. Thus, the nor-

mal path of the effect filling yarns **E1** to **E4**, inclusive, would be interrupted, these fillings being distorted or caused to turn upward at the left-hand portions thereof in Figure 7 and the right-hand portions of these effect fillings **E1** to **E4**, inclusive, would be caused to extend substantially in a straight line.

Thus, upon the tightly woven area defined by the warp yarns in group **1** and the filling yarns in group **2A** being woven and the loosely woven area, including the warp yarns in group **2** and the filling yarns in group **2A**, being woven, the tightly woven area, including the warp yarns in group **1** and the filling yarns in group **2A** will be disposed in off-set relation to the tightly woven area, including the warp yarns in group **2** and the weft or filling yarns in group **1A**, with the upper edge of the tightly woven area having the filling yarns in group **2A** being disposed substantially midway of the tightly woven area, having the warp yarns in group **2** and the weft yarns in group **1A** therein.

Now, due to the fact that the floated portion of the warp yarn, such as the warp yarn **W4** in group **2**, extends above all of the ground filling yarns in group **2A** as well as the bordering effect filling yarns **E4** and **E1'** and the warp yarns on each side of the warp yarn **W4** passes beneath the effect filling yarns **E4** and **E1'** but over the effect filling yarns **E3** and **E2'**, it is evident that upon the right-hand portions of the effect filling yarns **E1'**, **E2'**, **E3'** and **E4'** being beat-up against the effect filling yarns **E4**, the two adjacent effect filling yarns **E4** and **E1'** will be beat-up against each other and the yarns **E3** and **E2'** adjacent the remote surfaces of the yarns **E4** and **E1'** will tend to move beneath the yarns **E4** and **E1'** therebetween in the course of other beat-up strokes of the lay **36**. The same is substantially true of the remaining effect filling yarns **E2**, **E1**, **E3'** and **E4'** resulting in the effect or design filling yarns extending in a sinuous path and forming an embossed sinuous design on the ground fabric area substantially as shown in Figures 2 and 3, this also being clearly illustrated in Figures 5 and 6.

Now, due to this particular arrangement of the effect filling yarns adjacent the areas having floated yarns therein, upon the fabric being passed through various finishing operations, such as vigorous tumbling and washing operations, the floated warp yarns, which extend across the loosely woven areas between adjacent spaced tightly woven areas, tend to shrink a greater amount than do the tightly woven areas since it is evident that a loose or single yarn will shrink a greater amount than will a plurality of tightly interwoven yarns.

This causes the tightly woven areas to be pulled slightly towards each other and, in so doing, the distorted or sinuous effect filling yarns are caused to roll under each other, this being partly due to the fact that the warp yarns which are floated over the ground filling yarns also extend above the two adjacent effect filling yarns while the next adjacent floated or face warp yarns on each side of this first-named warp yarn extend beneath the immediately adjacent effect filling yarns, such as the effect filling yarns **E1'** and **E4** in Figure 7, and pass above the next adjacent effect filling yarn but pass beneath the remaining effect filling yarns, this being repeated for as many effect filling yarns as there may be disposed between the tightly woven warpwise extending areas.

It is thus seen that the floated portions of the warp yarns tend to lead the effect yarns which are immediately adjacent the spaced tightly woven areas 40 beneath the yarns which are disposed at the juncture of adjacent sinuous areas, this being clearly shown in Figure 4. It is also seen that a substantial distortion of the effect filling is caused by the dense and firmly woven portions of the fabric exerting a pressure against the effect filling yarns as the fabric is woven and, since there is no interfering back pressure on the effect fillings from the opposite open sleazy portions 41 of the fabric, the effect filling yarns will be forced over the portions 41 meeting the immediately adjacent group of effect filling yarns which are forced into the adjacent sleazy portions 41 of the fabric from the opposite side thereof.

Now, although there are shown twenty-six ground filling yarns between each of the groups of effect filling yarns and four effect filling yarns between the groups of ground filling yarns, it is evident that the number of effect filling yarns as well as the ground filling yarns may be decreased or increased in accordance with a desired pattern. However, it has been found that the most favorable results are obtained by providing repeats of the ground weft or filling yarns including five yarns in each repeat with the fifth weft yarn being interwoven with the third warp yarn in each instance in weaving the floated areas in the manner in which the warp yarns W3, in Figure 7, is interwoven with the weft yarn F6. The particular effect filling yarns shown in the drawings appear to be about three times the diameter of the ground warp and filling yarns and it is preferable that these effect filling yarns be plied with relatively low twist in the plied yarns to form a scalloped outline to the effect yarns in the cloth. For other effects, hard twisted or fancy effect filling yarns may be employed.

It is to be understood that the yarn from which the effect filling is formed may be identical to the yarn from which the ground fabric area is formed, the types of yarn employed in weaving the ground fabric area and the design areas formed of the effect filling yarns varying in accordance with a desired pattern effect to be produced. A fabric woven in accordance with the present invention may be employed in the manufacture of bedspreads, draperies, upholstery and the like.

Although, a relatively plain weave is shown in the drawings as representative of the tightly woven areas 40, this plain weave may be substituted with a fancy weave wherein various designs may also be incorporated, although, in this instance, the amount of distortion of the effect filling yarns as they are beat-up by the reed 35 may be relatively substantially reduced, the greatest amount of distortion in the effect filling yarns being obtained with a plain weave.

The manner in which the selvage is formed in a fabric woven in accordance with the features of this invention is shown in the right-hand portions of Figures 2 and 3. It is evident that upon four effect filling yarns being thrown across the lay 36, the effect filling yarns may be severed as the tightly woven areas of the ground fabric are woven so that the starting point of the next group of four effect filling yarns will not be encumbered by the portions of the yarn which may extend across the tightly woven areas at the selvages of the fabric.

However, considerable time would be consumed in performing this operation or special equipment may be required for this purpose. Therefore, it is preferable that the effect filling yarns extend along the selvage of the fabric adjacent the selvages of the tightly woven areas without being woven into the fabric as at 42 and, in order to prevent the selvage from being pulled inwardly at the loosely woven areas as a result of the effect filling yarns extending along the selvage of the tightly woven areas and entering the loosely woven areas, it is preferred that both the effect filling yarns and the ground filling yarns be held in alinement with the mean selvage of the fabric, as woven in the tightly woven areas, as it is woven in the loosely woven areas at the selvage of the fabric.

A typical apparatus which may be employed for this purpose is clearly shown in Figure 11 20 of my co-pending application, filed September 22, 1950, Serial No. 186,182 and entitled Pattern Controlled Variable Beat-Up and Pile Warp Feed Mechanisms. It is to be understood, however, that the manner of providing tension in the 25 weft yarns at the time of weaving the loosely woven areas adjacent the selvage of the fabric need not necessarily be limited to the apparatus shown in said co-pending application.

In the drawings and specification, there has 30 been set forth a preferred embodiment of the invention and although specific terms are employed, they are used in a generic and descriptive sense only and not for purposes of limitation, the scope of the invention being defined in the 35 claims.

I claim:

1. An improved fabric including a ground fabric area having warpwise extending rows of spaced tightly woven areas between which 40 loosely woven areas are disposed, the tightly woven areas in one row being off-set relative to the tightly woven areas in a next adjacent row so the loosely woven areas in the first-named row are disposed in weftwise alinement with the 45 tightly woven areas of said next adjacent row, design effect filling yarns loosely interwoven at the juncture of the tightly woven and loosely woven areas in each row and extending weftwise of the fabric throughout as much of the width 50 thereof as is embraced by the said rows of spaced tightly woven areas.

2. An improved fabric structure comprising a ground fabric area formed from a plurality of warp yarns and a plurality of ground weft yarns 55 and having at least two warpwise extending adjacent rows of spaced tightly woven areas and a loosely woven area being disposed between each of the tightly woven areas, the tightly woven areas in a first of said rows being disposed in substantially weftwise alinement with the loosely 60 woven areas of a second of said rows, a plurality of design filling yarns loosely interwoven with certain spaced warp yarns between each of the tightly woven areas in such a manner as to cause the design weft yarns to be interwoven with the warp yarns above the loosely woven areas formed from the ground weft yarns and the warp 65 yarns to cause the design weft yarns to extend in a sinuous path throughout as much of the width of the ground fabric area as is embraced by said rows, the design yarns deviating from their normal straight path at the juncture of adjacent rows of spaced tightly woven areas.

3. An improved fabric structure comprising a 70 ground fabric area woven from a plurality of

ground weft yarns and a plurality of ground warp yarns, said ground fabric area having at least two adjacent rows, namely, a first row and a second row, of weftwise spaced tightly woven areas therein between which loosely woven areas are disposed, the tightly woven areas in the second weftwise extending row being woven of the same warp yarns which are employed in weaving the loosely woven areas between the tightly woven areas of the first-named row, a loosely woven effect filling yarn being interwoven with certain spaced warp yarns for a predetermined number of picks in advance of weaving each of the loosely woven areas in the first row, the effect filling yarn also being interwoven with said few of the spaced ground warp yarns for a plurality of picks following the weaving of each of the tightly woven areas and in advance of weaving the adjacent tightly woven areas in the second row whereby the effect filling yarns will be forced over the loosely woven areas woven therebetween to cause the effect filling yarns to extend in a sinuous path in generally parallel relation to the ground weft yarns to effect an embossed appearance to the effect filling yarns on the ground fabric area.

4. An improved fabric including a ground fabric area having a plurality of juxtaposed warpwise extending rows of spaced tightly woven areas, said areas being defined by effect yarns extending transversely of the fabric in embossed relation to the ground fabric area and being interwoven therewith.

5. An improved fabric structure comprising a ground fabric area formed from a plurality of warp yarns and a plurality of ground weft yarns, said ground fabric area having warpwise and weftwise extending rows of spaced tightly woven areas and loosely woven areas disposed between the tightly woven areas, said tightly woven areas in adjacent rows being disposed in staggered relation to each other, each of said loosely woven areas being spanned by a plurality of floated portions of the warp yarns and also by a few spaced warp yarns interwoven with certain spaced ground weft yarns on the back of said ground fabric area, the floated portions of the warp yarns being disposed on the face of the ground fabric area, a plurality of embossing effect filling yarns interwoven at the juncture of the tightly woven and loosely woven areas with the floated portions of the warp yarns to cause the embossing effect yarns to occupy a position on the face of the ground fabric area above the loosely woven areas, and to thus cause the embossing effect filling yarns to extend across the face of the ground fabric area in generally parallel relation to the ground weft yarns in a sinuous line and whereby adjacent groups of the embossing effect filling yarns extend past the opposed edges of each of the tightly woven areas in juxtaposed relation at the loosely woven areas.

6. An improved fabric structure comprising a ground fabric area formed from a plurality of warp yarns and a plurality of ground weft yarns, said ground fabric area having warpwise and weftwise extending rows of spaced tightly woven areas and loosely woven areas disposed between the tightly woven areas, said tightly woven areas in adjacent rows being disposed in staggered relation to each other, each of said loosely woven areas being spanned by a plurality of floated portions of the warp yarns and also by a few spaced warp yarns interwoven with certain spaced ground weft yarns on the back of said ground fabric area, the floated portions of the warp yarns

being disposed on the face of the ground fabric area, a plurality of embossing effect filling yarns interwoven at the juncture of the tightly woven and loosely woven areas with the floated portions of the warp yarns to cause the embossing effect yarns to occupy a position on the face of the ground fabric area above the loosely woven areas, and to thus cause the embossing effect filling yarns to extend across the face of the ground fabric area in generally parallel relation to the ground weft yarns in a sinuous line and whereby adjacent groups of the embossing effect filling yarns extend past the opposed edges of each of the tightly woven areas in juxtaposed relation at the loosely woven areas, each of said tightly woven areas including successive repeats of a plurality of warp yarns wherein each repeat of the warp yarns includes a number of warp yarns substantially equal to twice the number of embossing effect filling yarns which extend across the upper surface of the loosely woven areas, the substantially centermost of each of the floated warp yarns in each repeat extending above the two contiguous of adjacent groups of embossing effect filling yarns, the next adjacent floated warp yarns on opposed sides of said centrally disposed floated warp yarn passing beneath the said contiguous embossing effect filling yarns and above the next adjacent embossing effect filling yarns disposed on opposed sides of said contiguous yarns and then beneath the remaining embossing filling yarns in said two adjacent groups to cause the contiguous embossing effect filling yarns to assume a higher position relative to the face of the ground fabric area as it is woven than the adjacent embossing effect filling yarns.

7. An improved fabric structure comprising a ground fabric area formed from a plurality of warp yarns and a plurality of ground weft yarns, said ground fabric area having warpwise and weftwise extending rows of spaced tightly woven areas and loosely woven areas disposed between the tightly woven areas, said tightly woven areas in adjacent rows being disposed in staggered relation to each other, each of said loosely woven areas being spanned by a plurality of floated portions of the warp yarns and also by a few spaced warp yarns interwoven with certain spaced ground weft yarns on the back of said ground fabric area, the floated portions of the warp yarns being disposed on the face of the ground fabric area, a plurality of embossing effect filling yarns interwoven at the juncture of the tightly woven and loosely woven areas with the floated portions of the warp yarns to cause the embossing effect yarns to occupy a position on the face of the ground fabric area above the loosely woven areas and to thus cause the embossing effect filling yarns to extend across the face of the ground fabric area in generally parallel relation to the ground weft yarns in a sinuous line, whereby adjacent groups of embossing effect filling yarns extend past the opposed edges of each of the tightly woven areas in juxtaposed relation at the loosely woven areas, said floating portions of the warp yarns being divided into groups in which the number of floated portions of the warp yarns is substantially equal to twice the number of embossing effect filling yarns, the centermost of each group of floated portions of the warp yarns extending over the adjacent contiguous or juxtaposed portions of the embossing effect filling yarns, the next adjacent floated portions of the warp yarns at op-

11

posed sides of the substantially centrally disposed floated portion of the warp yarn being successively passing beneath and then above the successive embossing effect filling yarns so that only one of the floated portions of the warp yarns is passed above any one of the embossing effect filling yarns in each group.

8. An improved fabric structure comprising a ground fabric area formed from a plurality of warp yarns and a plurality of ground weft yarns, 10 said ground fabric area having warpwise and weftwise extending rows of spaced tightly woven areas and loosely woven areas disposed between the tightly woven areas, said tightly woven areas in adjacent rows being disposed in staggered relation to each other, each of said loosely woven areas being spanned by a plurality of floated portions of the warp yarns and also by a few spaced warp yarns interwoven with certain spaced ground weft yarns on the back of said ground fabric area, the floated portions of the warp yarns being disposed on the face of the ground fabric area, a plurality of embossing effect filling yarns interwoven at the juncture of the tightly woven and loosely woven areas with the floated portions of the warp yarns to cause the embossing effect yarns to occupy a position on the face of the ground fabric above the loosely woven areas, and to thus cause the embossing effect filling yarns to extend across the 30 face of the fabric area in generally parallel relation to the ground weft yarns in a sinuous line and whereby adjacent groups of the embossing effect filling yarns extend past the opposed edges of each of the tightly woven areas 35 in juxtaposed relation at the loosely woven areas, said floated portions of the warp yarns extending across the loosely woven areas being interwoven at their junctures with the tightly woven areas with the embossing effect filling yarns in 40 a staggered manner wherein the portions of the embossing effect filling yarn disposed adjacent

12

the loosely woven areas pass beneath predetermined spaced floated portions of the warp yarns and above those floated portions of the warp yarns disposed between said spaced floated portions of the warp yarns and the next adjacent embossing effect filling yarn is passed beneath floated portions of the warp yarns which are passed beneath the first-named embossing effect filling yarn, and this being repeated according to the number of embossing effect filling yarns employed in weaving the fabric.

9. An improved fabric structure comprising a ground fabric area woven from a plurality of ground weft yarns and a plurality of warp yarns, a plurality of design weft yarns each extending above and weftwise of the ground fabric area and being interwoven with some but not all of the warp yarns, weftwise spaced portions of some of the ground weft yarns beneath the design weft 20 yarns being interwoven with the remaining warp yarns and other weftwise spaced portions of the ground weft yarns between the first-named spaced portions being interwoven with all of the warp yarns to cause the design weft yarns to extend in a sinuous line between each selvage of the fabric.

IVAR O. MOBERG.
